UNITED STATES PATENT OFFICE

JOSEPH NIGHTINGALE, OF PATERSON, NEW JERSEY.

DESIGN FOR A HANDKERCHIEF.

Specification forming part of Design No. **11,134**, dated April 1, 1879; application filed February 4, 1879.
[Term of patent 3½ years.]

To all whom it may concern:

Be it known that I, JOSEPH NIGHTINGALE, of the city of Paterson, in the county of Passaic and State of New Jersey, have originated and designed a Pattern for Silk Handkerchiefs or other Silk Fabrics, of which the following is a full, clear, and exact description, reference being had to the accompanying drawing, making part of this specification.

A represents the center or ground of the handkerchief, and the remainder of the figures and stripes outside of the ground A constitute the border of the design.

The center or ground A consists of a woven water-mark, the principal outlines of which are represented by the line-shading of the drawing.

The border B consists of ferns and fox-gloves, with the leaf C in each corner where the borders B would intersect if produced.

The border is separated from the center or ground by the stripes $s' s'$, which extend from side to side of the design, and is bounded on the outside by the marginal stripes S S, the stripes $s' s'$ and S S having twilled cords c c running through their centers for their respective full lengths. Harmonious colors should be employed to produce the best effect.

What I claim as my invention is—

The design for a silk handkerchief, consisting of the woven water-mark ground A, the border B, composed of fern-leaves and fox-gloves, and the stripes S S and $s' s'$, substantially as described, and shown in the accompanying illustration.

JOSEPH NIGHTINGALE.
